(57) **CLAIM**

The ornamental design for an insert for concealing a fastener hole, as shown and described.

DESCRIPTION

FIG. 1 is a top perspective view of an insert for concealing a fastener hole, showing our new design.

FIG. 2 is a side perspective view of the insert.

FIG. 3 is a bottom perspective view of the insert.

FIG. 4 is a top view of the insert.

FIG. 5 is a front view of the insert.

FIG. 6 is a bottom view of the insert.

FIG. 7 is a right side view of the insert; and,

FIG. 8 is a left side view of the insert.

The broken lines shown in FIGS. 1-8 are for illustrative purposes only and form no part of the claimed design.

1 Claim, 3 Drawing Sheets
